CLAIM

The ornamental design for a loud speaker system for
emergency vehicles, as shown and described.

DESCRIPTION

FIG. 1 is a front view of a loud speaker system for
emergency vehicles showing my new design;

FIG. 2 is a side view thereof, the device having the
identical appearance when viewed from the opposite
side;

FIG. 3 is a top view thereof;

FIG. 4 is a rear view thereof; and,

FIG. 5 is a bottom view thereof.

FIG. 4

FIG. 2

FIG. 5
